UNITED STATES PATENT OFFICE.

JAMES B. CALKINS, OF PACIFIC, MISSOURI.

IMPROVEMENT IN WATER-TANKS FOR RAILWAY STOCK-CARS.

Specification forming part of Letters Patent No. 136,132, dated February 25, 1873.

To all whom it may concern:

Be it known that I, JAMES B. CALKINS, of Pacific, in the county of Franklin and State of Missouri, have invented a new and useful Improved Water-Tank for Railway Stock-Cars; and I do hereby declare that the following is a full and true description thereof, reference being had to the accompanying drawing and to the letters of reference marked thereon.

This invention relates to the construction and arrangement of a water-tank car, for purposes chiefly of supplying feed-water to a train of stock-cars. The water-tank is provided with a pump operated by the axle of the truck, and having proper hose-connections with the cars, all of which will now more fully appear.

To enable those herein skilled to make and use my said improvement, I will now more fully describe the same, referring to—

Figure 1 as a longitudinal sectional elevation; to Fig. 2 as a transverse section.

A suitable water-tank, A, is constructed and supported upon ordinary car-trucks. The said water-tank car is arranged back of the locomotive-tender by tubes or pipes a a' , so that in filling the tender the water at the same time will flow through pipe a and fill the car-tank A. On top of the car-tank is securely

arranged a suitable force-pump, B, the supply-pipe b of which passes into the tank. (See Figs. 1 and 2.) The discharge passes through hose b' , which connects with and distributes water to the different cars.

In order to operate the pump there is arranged on the axle c of the truck the pulley c^1 , connecting by belting C with pulley c^2 on the top shaft c^3 . The said top shaft is supported in proper standards D, and is further provided with a crank, d, which communicates the required reciprocating motion to the pump-piston by pitman d^1 .

The tank A is constructed with a walled opening or well, d^2 , for the passage and accommodation of the belting-connections.

Having thus fully described my said invention, what I claim is—

The tank A, pump B, operated by axle c , pulleys c^1 c^2 , belting C, top shaft c^3 , crank-disk d , pitman d^1 , when arranged to operate as and for the purpose set forth.

In testimony of said invention I have hereunto set my hand.

JAMES B. CALKINS.
